[57] CLAIM

The ornamental design for hot pot base portion, as shown and described.

DESCRIPTION

FIG. 1 is a rear, right side and top perspective view of a hot pot base portion according to the present invention.

FIG. 2 is a front view of the hot pot base portion of FIG. 1. FIG. 3 is a right side view of the hot pot base portion of FIG. 1.

FIG. 4 is a rear view of the hot pot base portion of FIG. 1. FIG. 5 is a left side view of the hot pot base portion of FIG. 1.

FIG. 6 is a bottom view of the hot pot base portion of FIG. 1; and,

FIG. 7 is a top view of the hot pot base portion of FIG. 1. The broken lines are provided in the drawings merely for illustrating the environment in which the invention is used. The broken lines do not form part of the design sought to be patented.
